DESIGN FOR A CAN OPENER

Albert M. Travis, Kansas City, Kans., assignor
to John C. Hockery, Kansas City, Mo., as
trustee

Application October 18, 1946, Serial No. 134,025

Term of patent 14 years

(Cl. D22—2)

To all whom it may concern:

Be it known that I, Albert M. Travis, a citizen of the United States, residing at Kansas City, in the county of Wyandotte and State of Kansas, have invented a new, original, and ornamental Design for a Can Opener, of which the following is a specification, reference being had to the accompanying drawing, forming part thereof, in which

Fig. 1 of the drawing is a perspective view showing one side of a can opener embodying my new design, and

Fig. 2 of the drawing is a perspective view showing the reverse side of a can opener shown in Fig. 1.

I claim:

The ornamental design for a can opener, substantially as shown.

ALBERT M. TRAVIS.
